COATING APPARATUS

Edward H. Hillman, deceased, late of Steubenville, Ohio, by Grace E. Fellows, Youngstown, and Walter F. MacQueen, Niles, Ohio, administrators, assignors to National Steel Corporation, Pittsburgh, Pa., a corporation of Delaware

Application July 31, 1942, Serial No. 453,080

6 Claims. (Cl. 91—12.5)

This invention relates generally to the application of a protective coating to sheet material and, specifically, to an apparatus for galvanizing ferrous sheets.

In the galvanizing of sheet metal, the usual process is to first clean the sheet, then pass it through a pot of molten zinc. At the entrance end of the pot it is customary to float a body of molten flux, such as molten sal ammoniac, and in order to keep the flux in place, a box is used which is in the form of a hollow rectangle supported on the sides of the pot. The flux serves to prevent the formation of oxide on the surface of the molten zinc which would stick to the surface of the sheets to be coated and either give a very rough coating or prevent complete adherence of the coat to the base. The flux also serves to clean the metal at the instant it strikes the molten bath and to insure a dry surface before the metal passes into the molten zinc. This flux is continuously used up during the galvanizing process and must be continuously replaced. In the past, the operator occasionally threw a shovel full of sal ammoniac crystals into the pot to keep the level of flux about the proper height. This was extremely wasteful of the sal ammoniac, and the present invention is to eliminate such waste by automatically feeding a measured quantity of sal ammoniac crystals to the galvanizing pot.

Thus, the primary object of the present invention is to provide in a galvanizing apparatus means for automatically supplying a definite amount of fluxing salts, such as sal ammoniac, at definite intervals or continuously.

Other objects and advantages of the present invention are to provide a flux feeding apparatus that will be superior in point of simplicity, inexpensiveness of construction, positiveness of operation and general efficiency.

Further advantages of the invention will become apparent during the course of the following detailed description taken in connection with the accompanying drawings in which:

Figure 1 is a longitudinal sectional view of the galvanizing apparatus including the novel flux feeder;

Figure 2 is a plan view of a portion of the feeder;

Figure 3 is a sectional view of a major portion of the flux feeding apparatus.

Referring more particularly to the drawings, there is provided a metal coating apparatus which represents for the most part, a conventional construction and will, therefore, be de-

scribed only generally. It comprises a galvanizing pot 10 mounted on a suitable foundation and adapted to contain a bath of molten zinc or other liquid coating material 11. Entrance rolls 12 and 13 are suitably mounted above and adjacent one edge of the pot 10 and receive metal sheets advancing between guides 14 and 15 and direct them between guides 16, through a flux box 17 and thence between guides 18. Bottom feed rolls 19 deliver the sheets to guides 20 which guide them to exit rolls 21 disposed adjacent the discharge end of pot 10.

The feed-in rolls 22 and 23 are supported on a post 24 spaced a slight distance from the galvanizing pot 10. A sprocket gear 25 is connected to the shaft carrying the roller 12 and a cooperating sprocket gear 26 is connected to the shaft carrying the roller 22. A sprocket chain 26a connects the two sprocket gears 25 and 26. Springs 27 and 28 are provided to press rollers 13 and 23 against rollers 12 and 22 respectively. A suitable source of power, not shown, through the sprocket and chain drive, drives the feed-in rolls to feed the sheets of metal to the galvanizing pot.

The novel portion of the disclosed mechanism is the automatic flux feeding apparatus. This apparatus comprises a hopper 29 mounted on a pair of supporting bars 30 which in turn are connected to frame 31 supported on post 24. A frame member 32 supports the forward ends of bars 30 in such manner that hopper 29 is inclined towards the galvanizing pot.

Mounted within the rear end of hopper 29 is a shaft 33 rotatably connected to the side walls of the hopper. A sprocket or guide wheel 34 is mounted on shaft 33 and drives a conveyer chain 35 which in turn is connected to sprocket or guide wheel 36 mounted on rotating shaft 37 suitably supported on frame member 32. A bucket 38 of carefully predetermined capacity is mounted on conveyer chain 35. Although a single bucket has been shown, any number of buckets may be used if desired, consistent with their size and the speed of the chain.

A sprocket gear 39 is mounted on shaft 37 and is driven by sprocket chain 40 connected to sprocket gear 41 mounted on the shaft carrying roller 22. Thus the same source of power which feeds the sheets to the galvanizing pot will operate the conveyer chain to feed the sal ammoniac crystals 42 to the galvanizing pot. If desired, the conveyer chain may be driven from a different source of power.

It will be observed that operation of the chain

drive for the flux feeder will cause the bucket to pass through the flux crystals 42, filling the bucket, and as the bucket turns about sprocket wheel 36, the crystals are dumped into the galvanizing pot. Thus a constant, measured supply of sal ammoniac crystals are supplied to the galvanizing pot. The amount of crystals supplied can be varied by varying the size of the bucket or the speed of the conveying system.

While there has been shown and described a preferred embodiment of the invention, it is to be distinctly understood that the same is not limited thereto, but may be otherwise variously embodied within the scope of the following claims.

What is claimed is:

1. A device of the character described comprising a galvanizing pot, a receptacle adjacent the pot for holding a flux in crystalline or granular form, a conveyor passing into and out of the receptacle and receptacle means on the conveyor arranged to pick up flux in the receptacle and deposit the same in the pot.

2. A device of the character described comprising a galvanizing pot, a receptacle adjacent the pot for holding a flux in crystalline or granular form, a conveyor passing into and out of the receptacle, receptacle means on the conveyor arranged to pick up flux in the receptacle and deposit the same in the pot, sheet feeding rolls associated with the pot, and means for driving the feeder rolls and conveyor from a single source of power.

3. A device of the character described comprising a galvanizing pot, a receptacle adjacent the pot for holding a flux in crystalline or granular form, conveyor means operating between a point in the receptacle and a point above the pot, receptacle means on the conveyor, and means associated with the conveyor for causing

the receptacle means to pick up flux in the receptacle and deposit the same in the pot.

4. A device of the character described comprising a galvanizing pot, a receptacle adjacent the pot for holding a flux in crystalline or granular form, conveyor means operating between a point in the receptacle and a point above the pot, receptacle means on the conveyor, means associated with the conveyor for causing the receptacle means to pick up flux in the receptacle and deposit the same in the pot, sheet feeding rolls associated with the pot, and means for driving the feeder rolls and conveyor from a single source of power.

5. A device of the character described comprising a galvanizing pot, a receptacle adjacent the pot for holding a flux in crystalline or granular form, a guide wheel in the receptacle, a guide wheel above the pot, a continuous conveyor operatively engaging the guide wheels, receptacle means on the conveyor, and means associated with the conveyor for causing the receptacle means to pick up flux in the receptacle and deposit the same in the pot.

6. A device of the character described comprising a galvanizing pot, a receptacle adjacent the pot for holding a flux in crystalline or granular form, a guide wheel in the receptacle, a guide wheel above the pot, a continuous conveyor operatively engaging the guide wheels, receptacle means on the conveyor, means associated with the conveyor for causing the receptacle means to pick up flux in the receptacle and deposit the same in the pot, sheet feeding rolls associated with the pot, and means for driving the feeder rolls and conveyor from a single source of power.

GRACE E. FELLOWS,
WALTER F. MACQUEEN,
Administrators of the Estate of Edward H. Hillman, Deceased.
